ELECTROLUMINESCENT DEVICE

Moe Wasserman, Massapequa Park, N.Y., assignor to Sylvania Electric Products Inc., a corporation of Delaware

Filed July 14, 1959, Ser. No. 827,126

5 Claims. (Cl. 313—108)

My invention relates to electroluminescent devices.

One type of electroluminescent device known to the art comprises separate photoconductive and electroluminescent layers electrically connected in series. The photoconductive impedance in the dark is high relative to the electroluminescent impedance. Further, when the photoconductive layer is illuminated, the photoconductive impedance is significantly reduced. These layers are so arranged that a portion of the light emitted from the electroluminescent layer (when this layer is excited by applying a voltage across the series connected layers), impinges on the photoconductive layer.

As a result, when a voltage is applied between the two layers and the photoconductive layer is in the dark, the electroluminescent layer remains quiescent and emits substantially no light. The device is then in its first, or unexcited, electric state.

However, when a voltage is applied between the two layers and the photoconductive layer is stimulated by a light signal, the impedance of the photoconductive layer decreases sharply; consequently, a larger portion of the applied voltage appears across the electroluminescent layer and light is emitted. The device is then in its second, or energized, state. As long as the photoconductive layer remains illuminated by light from the electroluminescent layer, the device will remain energized despite removal of incident light. Conventionally, the device is deenergized by removing the applied voltage.

Such known devices, however, have certain inherent disadvantages. More particularly, the sensitivity of the device depends upon the ratio of the dark photoconductive impedance to the illuminated photoconductive impedance. Since only the light receiving surfaces of the photoconductive layer are excited by incident light, this ratio decreases as the thickness of the photoconductive layer increases. Stated differently, high device sensitivities require thin photoconductive layers.

On the other hand, for bistable operation, the dark impedance of the photoconductive layer should be high relative to the impedance of the electroluminescent layer. Since the dark photoconductive impedance increases with increasing thickness of the photoconductive layer, the photoconductive layer must be relatively thick for this type of operation.

As a result, electroluminescent devices of the type described above utilize relatively thick photoconductive layers and, consequently, have low sensitivity.

In accordance with the principles of my invention, my electroluminescent device comprises first, second and third transparent electrodes, an electroluminescent layer interposed between the second and third electrodes, and a photoconductive layer interposed between the first and second electrodes. The first electrode is smaller in area than the second electrode. The surface area of the photoconductive layer is substantially equal to the surface area of the electroluminescent layer.

By varying the ratio of the first electrode area to the second electrode area, the dark impedance of the photo-

conductive layer can be varied accordingly; i.e. as the ratio of these electrode areas decreases or increases, the dark impedance is increased or decreased. Further, the photoconductive layer can be extremely thin, thus permitting high device sensitivity. In other words, in my invention the device sensitivity and the dark photoconductive impedance are separate and independent parameters which can be controlled independently.

An illustrative embodiment of my invention will now 10 be described with reference to the accompanying figure.

Referring now to the figure, there is shown a bistable electroluminescent device having a first transparent electrode 10, a second transparent electrode 14 and a third transparent electrode 18. A photoconductive layer 12 15 is interposed between electrodes 10 and 14. An electroluminescent layer 16 is interposed between electrodes 14 and 18. The entire structure including electrode 18 is supported on a glass substrate 20.

The electrodes 10, 14 and 18 can be transparent tin 20 oxide films. The photoconductive layer can be composed of cadmium sulfide particles, activated with copper, coactivated with a chloride, and embedded in a glass enamel, as disclosed, for example, in my copending patent application Serial No. 796,155, filed February 27, 1959 now Patent No. 2,937,353. The electroluminescent 25 layer can comprise a dispersion of electroluminescent (copper activated zinc sulfate) particles also embedded in a glass enamel. Typically, the electroluminescent layer can be 1.5-2.5 mils thick. The photoconductive 30 layer typically can be 2-5 times as thick as the electroluminescent layer.

As shown in the figure, the area of the first electrode is smaller than the area of the second electrode. By adjusting the ratio of the area of the first electrode to 35 that of the second electrode, the dark photoconductive impedance can be suitably adjusted for a photoconductive layer of given thickness. More particularly, as this ratio decreases, the dark impedance is increased. Typically, this ratio can fall within the range 0.25-0.50.

In the device thus far described, bistable operation is 40 obtained in the manner previously indicated. Alternatively, the first electrode 10 can be opaque. The electroluminescent layer 16 is sufficiently thin to permit incident light to be directed through layer 16 and electrode 18 upon the photoconductive layer 12, thus again obtaining 45 bistable operation.

If desired, the second transparent conductive layer 12 in the above structure can be replaced by an opaque conductive film. Under these circumstances, however, 50 the electroluminescent layer will be energized only when the photoconductive layer is illuminated by incident light. As soon as the incident light is removed, the electroluminescent layer will be deenergized and emit no light.

What is claimed is:

1. An electroluminescent device comprising first, second and third electrodes, the third electrode and at least one of the first and second electrodes being transparent, the area of the first electrode being less than that of said second electrode, the ratio of the area of the first electrode to that of the second electrode falling within the approximate range of 0.25-0.50; an electroluminescent layer interposed between said second and third electrodes; and a photoconductive layer interposed between said first and second electrodes, the surface areas of both of said layers being substantially equal.
2. An electroluminescent device comprising first, second and third electrodes, the first and third electrodes being transparent, the area of the first electrode being less than that of said second electrode, the ratio of the area of the first electrode to that of the second electrode falling within the approximate range of 0.25-0.50; an electroluminescent layer interposed between said second

and third electrodes; and a photoconductive layer interposed between said first and second electrodes, the surface areas of both of said layers being substantially equal.

3. An electroluminescent device comprising first, second and third electrodes, the second and third electrodes being transparent; the area of the first electrode being less than that of said second electrode, the ratio of the area of the first electrode to that of the second electrode falling within the approximate range of 0.25-0.50; an electroluminescent layer interposed between said second and third electrodes; and a photoconductive layer interposed between said first and second electrodes, the surface areas of both of said layers being substantially equal.

4. An electroluminescent device comprising first, second and third electrodes, the first, second and third electrodes being transparent, the area of the first electrode being less than that of said second electrode, the ratio of the area of the first electrode to that of the second electrode falling within the approximate range of 0.25-0.50; an electroluminescent layer interposed between said second and third electrodes; and a photoconductive layer interposed between said first and second electrodes.

20

electrodes, the surface areas of both of said layers being substantially equal.

5. An electroluminescent device comprising first, second and third electrodes, the first and third electrodes being transparent, said second electrode being opaque, the area of the first electrode being less than that of said second electrode, the ratio of the area of the first electrode to that of the second electrode falling within the approximate range of 0.25-0.50; an electroluminescent layer interposed between said second and third electrodes; and a photoconductive layer interposed between said first and second electrodes, the surface areas of both of said layers being substantially equal.
